CLAIM

The ornamental design for a pant cuff, as shown and described.

DESCRIPTION

FIG. 1 is a fragmentary front elevational view of a left pant cuff showing my new design;

FIG. 2 is a side elevational view thereof;

FIG. 3 is an opposite side elevational view thereof;

FIG. 4 is a rear elevational view thereof; and,

FIG. 5 is a bottom plan view thereof.

The broken line showing of the shoe in FIGS. 1-5 is illustrative of environmental structure only and forms no part of the claimed design.
